UNITED STATES PATENT OFFICE.

LAWRENCE B. WEST, OF CINCINNATI, OHIO.

BEAM FOR RAILROAD-TRACK FOUNDATIONS.

SPECIFICATION forming part of Letters Patent No. 706,619, dated August 12, 1902.

Application filed December 14, 1901. Serial No. 85,996. (No model.)

To all whom it may concern:

Be it known that I, LAWRENCE B. WEST, a citizen of the United States, residing at Cincinnati, in the county of Hamilton and State 5 of Ohio, have invented a new and useful Improved Beam for Railroad-Track Foundations Constructed of Bituminous Concrete, of which the following is a specification.

The object of my invention is to provide a 10 longitudinal beam or foundation for railway-tracks which will firmly support the rails, can be quickly and conveniently laid, will readily set or harden to permit the operation of cars upon the track soon after it is laid, will possess 15 a degree of elasticity to relieve the wear and tear upon the rolling-stock, and which can be raised and tamped up at any point without damaging the said beam or foundation.

20 With the above objects in view the invention consists of a longitudinal beam or foundation for railway-tracks composed of asphalt, coal-tar, or other bituminous products mixed with sand, crushed stone, and like material, 25 laid and tamped at the sides and bottom of the rail.

The invention further consists in the particular construction of the beam or foundation and its arrangement with respect to the 30 track-rail.

In the accompanying drawing, which forms a part hereof, the view is a sectional perspective view of my improved track-beam.

In carrying out my invention the beam or 35 foundation is composed of asphalt, coal-tar, or other bituminous products mixed with sand, crushed stone, granite, slag, or other material of a like nature in proper proportions, according to the hardness and elasticity 40 required. These ingredients are thoroughly mixed and heated to a plastic condition, and the material so formed is laid at the sides and under the track-rail and tamped to give the proper solidity and shape to the 45 beam. In this way the rail is embedded in the beam with the tread portion thereof flush with the upper surface of said beam, whereby the 50 said rail is firmly and securely held in place. It will be understood, of course, that in laying the beam where the surface of the adjoining pavement or ground is to be on a level,

or nearly so, with the top of the rail a trench is first dug of suitable width and depth and the rail temporarily supported therein during the operation of tamping the material around 55 the same. After the material sets and hardens, which takes place very rapidly—within a few hours—cars may be run upon the track. The rails may be trued after the material has set or hardened, as the elasticity or yielding 60 nature of the composition will permit it to be raised and moved laterally at any point a slight distance without damaging the construction of the beam.

As shown in the accompanying drawing, 65 the beam (designated by the letter A) is preferably wider at the base portion *a* than at the upper part *a'*, the sides of the latter converging slightly to the top, as shown, while the base portion is rectangular in cross-section. 70 Under ordinary conditions the beam will have a depth of about sixteen inches, a width of about sixteen inches at the base, and a width at the top of about ten inches; but these dimensions may be varied to suit conditions of 75 traffic and paving. In every instance, however, the rail B is disposed in the center of the upper portion of the beam; and the said rail is provided with the usual base-flange to insure a proper bearing in the beam, the latter 80 extending under said flange a suitable depth.

The advantages of a longitudinal track-beam constructed in accordance with my invention are many. Such a beam can be 85 quickly and conveniently laid, and as it rapidly hardens cars may be operated upon the track a few hours after it is constructed. This is of great importance to heavily-congested lines in large cities, where the loss of trackage 90 during the period of construction would result in demoralizing a running-schedule of numerous lines which are compelled to pass over one track. Such a condition is almost entirely obviated, inasmuch as the track is 95 ready to operate over within a few hours, or as soon as the artificial heat has left the asphalt or other bituminous product used. Another important advantage is the fact that the asphalt or bituminous beam may be raised 100 and tamped up to the proper level without damaging the beam construction, so that any

settling of the road-bed or spreading of the rails may be readily and quickly readjusted and without suspending operating of cars. This construction of beam will also be easy on the rolling-stock on account of its elasticity. These advantages are not attained by the ordinary hydraulic cement concrete beam commonly used, and which requires from ten days to two weeks under favorable weather conditions in order to reach the degree of hardness necessary to withstand the weight of cars passing over it. It is also obvious that from the nature of the materials used in the construction of my improved beam the same may be constructed during any season of the year.

Having thus described my invention, I claim—

1. A longitudinal track-beam surrounding the sides and bottom of a rail and composed of asphalt, coal-tar or other bituminous products mixed with sand, crushed stone and like material.
2. A longitudinal track-beam composed of asphalt, coal-tar or other bituminous products mixed with sand, crushed stone and like material laid at the sides and beneath the rail

and tamped, so that said rail will be embedded and supported therein.

3. A longitudinal track-beam composed of asphalt, coal-tar or other bituminous products mixed with sand, crushed stone and like material, and laid at the sides and beneath the rail and tamped so that said rail will be embedded and supported therein, the said beam being wider at the base than at the top.

4. A longitudinal track-beam composed of asphalt, coal-tar or other bituminous product mixed with sand, crushed stone or like material laid at the sides and beneath the rail, the top of the beam being flush with the top of the rail.

5. In a longitudinal track-beam for railways, the combination with the rail having a base-flange, of a beam composed of asphalt, coal-tar or other bituminous products mixed with sand, crush stone or similar material, and laid and tamped at the sides and beneath the base-flange of the rail, so that the said rail will be embedded in the beam.

L. B. WEST.
